Primary Examiner — Mark A Goodwin(74) *Attorney, Agent, or Firm* — Sanchelima & Associates, P.A.; Jesus Sanchelima; Christian Sanchelima(57) **CLAIM**

The ornamental design for cabinet door foot operation plate as shown and described.

DESCRIPTION

FIG. 1 is an isometric operational view of a cabinet door foot operation plate showing my new design;
FIG. 2 is a front elevational view thereof;
FIG. 3 is a rear elevational view thereof;
FIG. 4 is a left side elevational view thereof;
FIG. 5 is a right elevational view thereof;
FIG. 6 is a top plan view thereof; and,
FIG. 7 is a bottom plan view thereof showing my design.
FIG. 8 is an isometric view.
The broken lines in the drawings illustrate portions of the cabinet door foot operation plate which form no part of the claimed design.

1 Claim, 5 Drawing Sheets(56)
